(57) **CLAIM**

I claim the ornamental design for a knife with bottle opener, as shown and described.

DESCRIPTION

FIG. 1 is a left, top perspective view of a knife with bottle opener in an open configuration, showing my new design; FIG. 2 is a left-side elevation view thereof; FIG. 3 is a right-side elevation view thereof; FIG. 4 is a front elevation view thereof; FIG. 5 is a back elevation view thereof; FIG. 6 is a top plan view thereof; FIG. 7 is a bottom plan view thereof; FIG. 8 is a left, top perspective view of the knife in a closed configuration thereof; and, FIG. 9 is a left-side elevation view thereof. The broken lines illustrate portions of the knife with bottle opener that form no part of the claimed design.
